UNITED STATES PATENT OFFICE.

HANS PRYM, OF STOLBERG, GERMANY.

WIREWORKING MACHINE.

Application filed June 2, 1926, Serial No. 113,216, and in Germany June 27, 1925.

This invention relates to an improved wire clamping and feeding device for wire-working machines especially adapted for work with short but straight wire pieces.

5 Levers moved by cam disks and executing two different kinds of movements namely a movement perpendicular to the wire for clamping and another movement in the longitudinal direction of the wire for moving it, were used until now in the art. This double movement is not only uncomfortable, but affords too much force for clamping. The lever is subjected to a very strong strain of flexure and its end sliding on the cam disk becomes so hot for the high speed of the machine, that the lubricant evaporates. Furthermore the feeding carriages are very strongly loaded by the clamping pressure.

10 These disadvantages are avoided according to this invention, by only allowing the lever to move in one direction namely for feeding, whereas the wire is clamped by small tongs, which is closed by manifold leverage the closing only affording a very small pressure.

15 A construction of a device according to this invention is illustrated in the drawing, in which

Fig. 1 is a side elevation of a part of the wire-working machine showing the invention applied thereto, and

Fig. 2 is a vertical section thereof.

A double-armed lever *c* geared in a bearing *o* is reciprocated by the cam disk *b* on the driven shaft *a* of the machine. The lever *c* is connected by means of a rotatable joint *e* with a carriage *d* sliding in a straight line. Tongs *f* mounted below the joint *e* in the carriage *d* are closed from the shaft *a*. For this purpose the cam disk *g* on the shaft *a* swings the bent lever *h* about the pivot *h*², a roll *h*¹ of the lever *h* lying on said cam disk *g*. The movement of the bent lever *h* is transferred by the pin *i* onto an adjustable tappet *k*² of a double lever *k*. This lever *k* is mounted movably on the pivot *k*¹ of the lever *c* and presses by medium of a pin *l* on the movable side piece of the tongs *f*, thereby clamping the wire *g*. The pivot *k*² is journaled in a projection *p* of the bearing *o*. The tongs *f* are opened again by a small spring *m*, disposed between the side pieces of the tongs *f*, as soon as the roll *h*¹ of the bent lever *h* has run down

from the pitch of the cam disk *g*. Against the arm *k*¹ of the double lever *k* presses a spring *n* returning the latter. A rolling friction is present between the roll *h*¹ of the bent lever *h*. Due to the described construction the pressure which is necessary for clamping the wire is very small, because:

1. between the roller *h*¹ and the curved disk only rolling friction exists, and
2. because a large lever transmission is present between the curved disk *g* and the tong *f*.

The advantages of the new device are to be found in that the levers execute movements only in one direction, that the sliding carriages *d* are free from the pressure, which else was necessary for clamping the wire and that only a very slight pressure is sufficient for the clamping of the wire.

I claim:

1. In a device for clamping and feeding wires in wire-working machines, a slidable carriage for feeding the wire, a driven shaft, a cam disk on said shaft, a double lever moved by said cam disk and reciprocating said carriage, separate wire clamping means in said carriage and separate means mounted directly on the double lever for actuating said clamping means.
2. In a device for clamping and feeding wires in wire-working machines, a slidable carriage, a driven shaft, a cam disk on said shaft, a swinging double lever moved by said cam disk and engaging with said slidable carriage, clamping tongs in said slidable carriage and means actuating said clamping tongs including a lever pivoted to a double lever and directly engaging one of the tongs.
3. In a device for clamping and feeding wires in wire-working machines, a slidable carriage, a driven shaft, a cam disk on said shaft, a swinging double lever moved by said cam disk and engaging with said slidable carriage, clamping tongs in said slidable carriage, a second cam disk on said shaft, a bent lever moved by said cam disk, a second lever pivoted on the first mentioned lever and actuated by the bent lever and closing said tongs, a spring between the side-parts of said tongs, and a spring actuated arm on the second lever.

In testimony whereof I affix my signature.
HANS PRYM.
